UNITED STATES PATENT OFFICE.

JOHN T. PHILLIPS, OF LAFAYETTE, ALABAMA.

DESIGN FOR A FLOWER OR LAMP STAND.

Application filed July 3, 1923. Serial No. 6,671. Term of patent 14 years.

To all whom it may concern:

Be it known that I, JOHN T. PHILLIPS, a citizen of the United States, residing at Lafayette, in the county of Chambers and State of Alabama, have invented a new, original, and ornamental Design for Flower or Lamp Stands, of which the following is a specification, reference being had to the accompanying drawing, forming part thereof.

The figure is a perspective view of a flower or lamp stand showing my new design.

I claim:

The ornamental design for a flower or lamp stand as shown.

JOHN T. PHILLIPS.
